CLAIM

(51) **LOC (14) Cl.** **14-03**

The ornamental design for a sensor enclosure, as shown and described.

(52) **U.S. Cl.**

USPC **D14/230**

DESCRIPTION

(58) **Field of Classification Search**

FIG. 1 is an isometric view of a front, bottom, and left side of an ornamental design for a sensor enclosure;

USPC D14/230, 231-239, 241, 223, 206, 155,

FIG. 2 is a front elevational view of the sensor enclosure of FIG. 1;

D14/159, 217; D10/281, 53, 56, 96;

FIG. 3 is a rear elevational view of the sensor enclosure of FIG. 1;

D8/32, 377; D25/41.1, 43; D23/227,

FIG. 4 is a right side elevational view of the sensor enclosure of FIG. 1;

D23/219, 136, 266, 267; D6/601;

FIG. 5 is a left side elevational view of the sensor enclosure of FIG. 1;

D12/174

FIG. 6 is a top plan view of the sensor enclosure of FIG. 1; and,

CPC H01H 9/0242; H01H 9/025

FIG. 7 is a bottom plan view of the sensor enclosure of FIG. 1.

See application file for complete search history.
